COMBINATION DRESS AND APRON

Diamond Donner Sipe, New York, N. Y.

Application October 27, 1932. Serial No. 639,833

2 Claims. (Cl. 2—74)

This invention relates to ladies' dresses and particularly to house dresses of the type usually worn with aprons.

The principal purpose of the invention is to provide a dress and apron combination in which there is no appearance of an apron so that the wearer does not need to remove and put on the apron at frequent intervals while entertaining or when she is required to go from her work to receive a caller.

It has been observed that with ordinary house dresses and aprons, the housewife does not want to appear wearing an apron before strangers or before people whom she may be entertaining even though she may be required to go to the kitchen at frequent intervals. It is, therefore, necessary for her to spend a large amount of time in removing and putting on the apron each time she is required to go from one room to another.

Prior to my invention it has been extremely difficult to obtain a combination of a dress and apron in which it will not be observed that an apron is being used. The result accomplished by my invention is a complete blending of the apron into the dress so that it is practically impossible to determine that the wearer is using an apron. For this purpose it is preferable that the apron be made of the same material as the dress or at least of harmonious color.

Although the advantages of some of the features of my invention may be secured by the use of buttons or other usual fastening means, for joining the upper edge of the apron to the dress it is preferable to employ a continuous fastening means for the reason that when the wearer walks or bends her body, the apron will wrinkle at places and project outwardly from the dress thereby showing plainly that an apron is being worn, whereas with a continuous fastener the material of the apron in a sense "flows" with the dress and it is practically impossible to detect that an apron is being worn. It has been found that a well-known type of slide operated fastener having a separable end connection so that the sections can be completely separated, will serve my purpose better than any other known fastening means.

Further features of my invention are the complete concealment of the fastener whether or not the apron is in use and the ability quickly to attach and detach the apron.

A still further important feature is the outward curves of the sides of the apron at the bust line so that the apron will always have

the appearance of being a part of the dress and will fit neatly at this point to avoid the appearance of an apron.

In the accompanying drawing I have shown for purposes of illustration one embodiment 60 which my invention may assume in practice. In the drawing:

Fig. 1 is a view of a house dress and apron combination embodying my invention;

Fig. 2 is a vertical sectional view on line 2—2 65 of Fig. 1;

Fig. 3 is a view with the collar broken away showing the apron being detached from the dress;

Fig. 4 is a partial front view showing the 70 dress and fastener section attached thereto with the apron completely detached.

The dress may be of any well-known design and the one illustrated has a body fitting portion 7, arms portions 8, and a collar 9. Preferably the collar has a wide overhanging extension 10 as is common in dresses of this type, and which serves a useful purpose in the combination as will hereinafter appear. The apron 11 is preferably of the full length type shown in 80 Fig. 1 but differs from known designs in having the sides curved outwardly as shown at 12 at the bust line for giving neatness at this point and avoiding the outward bulging of the apron edge as in ordinary constructions. 85

For attaching the apron to the dress, use is made of a slide operated fastener which has two stringers 13, 14 with interlocking elements 15 on the edges thereof. These sections of the fastener are provided with a suitable separable 90 end connection preferably of a well-known type on the market, having a metal pin member 16 on the stringer carried by the dress and a metal socket member 17 on the stringer carried by the apron. It is desirable that the arrangement of the parts of the separable end connection be as specified in order that the slider 19 may, when the apron is detached, be taken off with the apron instead of being left on the dress where it would be objectionable. In operation the slider is moved to the right hand position as viewed in Fig. 3 and the slider is slipped over the metal pin member 16 until the parts are engaged. Then the slider may be quickly moved to the other end of the fastener and the attachment is complete. In taking the apron off all that is necessary is to move the slider toward the separable end connection and continue moving it until the socket 18 is slipped away from the pin 16. 100

110

As shown in Fig. 2, the stringer 13 of the fastener is sewed to the material of the dress and the thin finishing strip 20 is preferably applied so that the material of the fabric stringer will be neatly covered. It will be observed that the fastener sections are located behind the collar extension 10 so that they will be completely concealed thereby when the apron is in use, and the section 13 will be concealed when the apron is not being worn.

As a result of my invention it will be observed that an improved dress and apron combination has been devised in which it is practically impossible to detect the presence of an apron when the apron is being worn (see Fig. 1). It is, therefore, unnecessary for the housewife to remove and replace her apron at frequent intervals as above pointed out. The use of a slide fastener has the special advantages of extreme flexibility and continuous attachment, thereby making the apron hug tightly to the dress at all times. It, of course, has the further advantage of ease and quickness of attachment and detachment.

While I have in this application specifically described one embodiment which my invention may assume in practice, it will be understood that this embodiment is merely for the purpose of illustration and description and that various other forms may be devised within the scope of my invention as defined in the appended claims.

What I claim as my invention is:

1. A dress of the class described including a body fitting portion and a collar, a full length apron, a slide operated fastening means comprising cooperating sections, one attached to the dress under a portion of and completely covered by said collar and the other attached to and extending across the upper edge of said apron, and separable end connecting means on said sections whereby said apron may be quickly attached or detached from said dress, the whole of said fastening means and the upper edge of said apron being concealed by said collar. 80
2. A dress of the class described including a body fitting portion and a collar, an apron, and slide fastening means for quickly attaching and detaching said apron, said fastening means comprising a pair of fabric stringers which have interlocking fastener elements and a separable end connection thereon, one of said fabric stringers extending across the front of said dress under a portion of said collar and completely concealed thereby, and the other of said stringers being attached to and extending across the upper edge of said apron, and a finishing strip attached to the dress and covering the edge of said first mentioned stringer, the whole of said fastening means and the upper edge of said apron being concealed by said collar. 90
